UNITED STATES PATENT OFFICE.

JOHN W. KENNEDY, OF ROCHESTER, NEW YORK, ASSIGNOR TO THE SILL STOVE WORKS, OF SAME PLACE.

DESIGN FOR A FIRE-POT LINING.

SPECIFICATION forming part of Design No. 29,184, dated August 9, 1898.

Application filed July 18, 1898. Serial No. 686,291. Term of patent 14 years.

To all whom it may concern:

Be it known that I, JOHN W. KENNEDY, a citizen of the United States, residing at Rochester, Monroe county, New York State, 5 have invented and produced a new and original Design for Fire-Pot Linings for Stoves and Ranges, of which the following is a specification, reference being had to the accompanying drawings, forming a part thereof.

10 Figure 1 is a perspective view of my design; Fig. 2, a top plan view of the same.

The leading feature of my design consists in the general shape and configuration of the fire-pot lining, as shown.

15 The front face 1 of the lining is curved and flares outwardly and upwardly from the bottom, the curve of the latter being semi-elliptical. The rear of the top is substantially straight, as in Fig. 2, being cut away at one 20 end to form the angular recess 2, and at the opposite end of the lining the top slopes down-

wardly and outwardly to form the rounded corner 3 above the substantially straight edge 4. To the right of the rounded corner the flare in the top is extended somewhat, as at 25 5, and upon the under side of this extension is a lug 6. The opposite or left-hand side of the lining extends backwardly and upwardly from the base, as shown, and is recessed at 8 below the overhanging rounded corner 9 of 30 the upper face. The lower edge of the lining is formed by the narrow flange 10. Arranged centrally upon the face 1 and near the top is a lug or projection 11.

What I claim is—

35 The design for a fire-pot lining, substantially as shown and described.

JOHN W. KENNEDY.
